UNITED STATES PATENT OFFICE.

JOHN S. FORBES, OF PHILADELPHIA, PENNSYLVANIA.

APPARATUS FOR HEATING AND STERILIZING.

SPECIFICATION forming part of Letters Patent No. 750,757, dated January 26, 1904.

Application filed February 27, 1903. Serial No. 145,305. (No model.)

To all whom it may concern:

Be it known that I, JOHN S. FORBES, a citizen of the United States, residing in Philadelphia, Pennsylvania, have invented certain Improvements in Apparatus for Heating and Sterilizing, of which the following is a specification.

My invention relates to improvements in apparatus for sterilizing liquids, having for its object the provision of a sterilizer designed, primarily, to operate upon and deliver liquid in such manner as to materially increase the efficiency of apparatus of the kind noted and to provide means by which the operation thereof is automatically regulated both as regards the operating-pressure, output of liquid, and the supply of heat for sterilizing said liquid. It is further desired to materially increase the capacity of a sterilizer of a given size, while at the same time so constructing the device that its parts shall be easily accessible for inspection and cleaning, the arrangement of the whole being such as to render practically impossible the passage of liquid therethrough without sterilization. These objects I attain as hereinafter set forth, reference being had to the accompanying drawings, in which—

Figure 1 is a sectional elevation, to some extent diagrammatic, illustrating one form of my improved apparatus. Fig. 2 is an elevation, partly in section, showing the detail construction of the float-operated valves of my improved apparatus, the same indicating the position of the floats relatively thereto.

In the drawings, A represents the external casing of my sterilizer, within which is contained the liquid-holding portion A' or casing proper of the sterilizer, both of these casings being supported upon a base-casting A². It will be seen that said casting is formed with a cavity or recess a, and between the top surface of said casting and an annular casting a' is confined a tube-sheet a², having a series of openings into which are expanded or otherwise suitably held a number of tubes a³, extending within the casing A'. This casing is made with an upper and lower part, which parts are united and operatively held together in the present instance by a chambered casting a⁴, having two annular cavities a⁵ and a⁶, there

being in the present instance a series of openings in that portion or wall of the casting a⁴ separating these two cavities, as well as a second and larger series of openings through the upper wall of the cavity a⁶. There are in the first of these openings a series of upwardly-projecting tubes a⁷, open at both ends and each surrounded and inclosed by a larger tube a⁸, which enters and is held in the second of said series of openings. These large tubes are closed at their upper ends and communicate with the interior of the cavity a⁶, from which leads a pipe a⁹, connected, if desired, to a steam-trap. I preferably form in the bottom of the cavity a⁵ a slight depression, (indicated at a¹⁰), and into this I extend one of the interior series of tubes a⁷, as shown. It will be seen that a top casting A' closes the upper portion of the casing A', which extends from the casting a⁴ outside of the various series of tubes a⁷ and a⁸, being of larger diameter than its lower portion. It will be understood that this casing is designed to contain the liquid to be sterilized or otherwise operated upon, while the space between it and the external casing A may be filled with some heat-non-conducting substance, as asbestos, so that it serves to effectually insulate said interior casing.

Supported in any suitable manner within the upper portion of the casing A' and inclosing within it all of the tubes a³ is an annular partition or confining-section B, open at both ends and having removably placed on its top a fluid-guiding section b, provided with a bottom in which are a series of openings b', having short downwardly-projecting sections of tubing so placed as to each enter the upper end of one of the tubes a³. The upper ends of said tubes are loosely held in their proper positions by a perforated plate b², which is supported from the under side of suitable brackets b³, projecting from the section B, and serves more particularly to properly space the tubes a³ when the guiding-section b is removed—as, for example, when the device is being inspected or cleaned. An annular inwardly-curved piece b² is fastened to the upper portion of the inner wall of the casing A' just above the section b for the purpose of turning inwardly the body of water 100

rising between the section B and the said casting, it being noted that the upper portion of said ring is of less diameter than its lower portion.

5 C is a supply-pipe through which liquid is delivered to the sterilizer, and there is in this a valve of any of the well-known forms (indicated in dotted lines at c) and having projecting from it a spindle c', the same entering a 10 float-chamber D, which may be supported, if desired, by means of its connections from the casing A'. Said supply-pipe C enters the casting a', so as to deliver liquid around the outside of the lower portions of the tubes a' 15 within the casing A', the distribution of said fluid being facilitated by means of an annular partition b', which so limits the opening from the casting a' to the space within the casing that the liquid flows into the latter from all 20 sides. A clean-out or blow-off valve c' is provided in the pipe C.

The connections of the float-chamber D consist of two pipes d and d', of which the first enters the upper portion of the casing A' at 25 a point above the section b or, in other words, above the highest point attainable by the water-level, while the second enters said casing at a point below the tops of the tubes a' in such position as to always be below the normal 30 water-level. A float d'' is attached to the valve-spindle c' by means of a rod d', the valve c being so constructed that it will be opened by downward movement of the float d'' from the position shown. A pressure-gage d' is operatively connected to the upper 35 portion of this float-chamber, while from its bottom part extends a pipe d'' to a pressure-regulator d'', placed to act upon a valve d' in a pipe d', through which steam or other heating fluid is supplied to the sterilizer, said pipe being connected in the present instance to the cavity a' in the casting a'. A connection d' leads from this pipe d' into the space surrounding the tubes a' within the casing A', 40 and this has in it a valve d'', by which the admission of steam to said space may be controlled. A steaming-out connection d'' also leads from this pipe d' into the space a, communicating with the interiors of the tubes a', 45 and this has in it a valve d'', by which the passage of steam thereto being governed by a valve d'.

An outlet-pipe E, having a cut-off valve e', (shown in dotted lines,) leads from the cavity a, formed in the base-casting A', and has a 55 blow-off or cleaning-out cock e. A second float-chamber F is provided with a float f, connected by a rod f' to the valve-spindle f' of the valve e' for the purpose of governing the flow of liquid through the pipe E, the said 60 chamber being connected by means of a pipe f' to the cavity a in the lower part of the casting A' and by a pipe f' to the upper portion or steam-space of the casing A'. This latter pipe enters the casing at a point above 65 the highest water-level, being arranged in the

same manner and that for the same reason as set forth in connection with the chamber D.

In operation water, milk, or other liquid to be sterilized is supplied through the pipe C, and after passing through the valve c and rising around the tubes a' it flows through the pipe d' into the float-chamber D until it has attained a level within the apparatus necessary to raise the float d'' sufficiently to close the valve c. Steam or any other desired heating fluid is then admitted through the pipe d', it being understood, however, that before commencing operations the interior of the device may be conveniently and effectually sterilized by admitting steam through the pipes 70 d'' and d''. The said heat fluid flows into and around the cavity a', flowing up through the tubes a' and through the tubes a' to the cavity a', finally passing out through the pipe a'. Should any of the heating fluid condense, 75 it would collect in the depression a'', formed in the bottom of the cavity a', and from time to time would be carried up through the downwardly-extended one of the tubes a' by the current of fluid passing into the same, so as to be finally discharged by the pipe a''. As soon as the water or liquid to be sterilized surrounds the heated tubes a' its temperature is raised until it reaches the point of ebullition. Under ordinary circumstances water at 80 this temperature frees or tends to free steam from its exposed surface with but relatively very little disturbance of its surface or change of level; but by the use of the partition-section B, I so restrict the possible surface at 85 which vapor can be freed that this action will only take place between said section and the inner wall of the casing A', it being noted that the body of liquid surrounding the tubes a' within the section B is not necessarily heated 90 to the boiling-point. Consequently when this external body of water reaches the boiling-point that portion of it within the upper part of the casing A' and outside of the partition B rises bodily and being guided inwardly by 95 the ring b' flows at a practically continuous rate over the weir formed by the upper edge of and into the guiding-section b into the tubes a'. Such body of liquid has therefore been heated, as required for sterilization, to a temperature at least equal to that of its boiling-point due to the predetermined temperature, 100 and it now flows through the tubes a' into the cavity a, rising in the pipe E until its level is the same as that within said tubes a'. The level of the raw or unsterilized liquid is kept at a constant level below the tops of the tubes a' by means of the float d'', as above noted, and since the particular sterilizer illustrated is air-tight as the heating of water continues 105 the pressure within the top part of the same will rise, thus tending to force the water out of the tubes a' and through the pipe E to a reservoir or to distributing-pipes. The float f, controlling the valve f', prevents all of the 110

water which has been sterilized from being thus blown or forced out of the apparatus through the pipe E, since when the said water has fallen to a predetermined level in the 5 tubes a^3 said float will close the valve e' . When this takes place, the pressure within the casing will continue to rise until finally the regulator d^6 will shut off or throttle the valve d' sufficiently to prevent further inflow of 10 steam to the heating-pipes or to so cut down the said inflow that there will be no further rise in said pressure. As the temperature within the casing falls, and consequently the pressure also, the regulator d^6 again opens the 15 valve d' and permits sufficient steam to flow in to again start the ebullition of the water and its consequent passage over the weir formed by the upper edge of the guiding vessel b and thence into the tubes a' , so that the 20 float f will again rise and open the valve e' .

It will be seen that the water within the tubes a^3 before it flows out through the pipe E parts with by far the greater portion of its heat to the incoming liquid rising around the 25 said tubes, so that a very perfect heat exchange is effected, and the water that finally passes out is at a temperature but very little higher than that of the inflowing liquid.

While I have described the operation of my 30 improved apparatus as intermittent, it will be understood that when the various elements thereof are properly adjusted the said operation is practically continuous.

By the use of the section B for restricting 35 the freeing-surface of the portion of the liquid being heated I materially increase the capacity of the sterilizer, since though relatively small volumes of the liquid are under treatment at any one time these are very quickly 40 raised to the boiling-point and pass away, so that there is a constant and rapid circulation within the device, which not only insures a relatively large amount of sterilized liquid for a given quantity of steam, but also prevents 45 the deposit of sediment or scale-forming substances in any part of the device.

By employing a pipe d to connect the float-chamber D with the main casing at points 50 above the water-level I am enabled to maintain the liquid at the same height in both of said vessels without having a constant circulation of that portion of said liquid in the float-chamber, the advantage of which lies in the fact that the same body of water remains 55 in this chamber and there is no deposit of scale formed.

The inwardly-curved ring b^2 prevents the water which is raised upwardly by the vapor within or under it from falling directly back 60 into the space between the section B and the inner wall of the casing, thus insuring its delivery into the compartment or receiving vessel b . Whenever it is desired to clean or inspect the upper portion of the interior of the

casing A', the guiding vessel b , with its bottom section b' , may be easily removed and the perforated sheet, which is normally held to the brackets b^5 by any desired form of catches, may be allowed to drop to the lower portion of said casing A. When the various parts are 65 again assembled, this piece b' on being raised insures the proper spacing of the upper ends of the tubes a^3 , which otherwise would be most troublesome to return to their original relative positions. 70

If desired, a safety-valve b^6 may be placed in connection with the top of the casing A', although under all except abnormal conditions the automatically-acting floats will actuate their respective mechanism to prevent any 80 undue rise of pressure. It will therefore be seen that by the use of my apparatus it is possible to force under pressure a practically constant amount of sterilized fluid to a reservoir or other center of distribution placed in an elevated position, at the same time so constructing the device that the probability of its failure to properly operate is reduced to a minimum. 85

I claim as my invention— 90

1. The combination in a sterilizer, of a casing, means for maintaining liquid normally below a predetermined level therein means for heating a portion of the liquid and means for carrying away heated liquid rising above the 95 predetermined level, together with means for limiting the steam-freeing surface of said portion of liquid to be treated, substantially as described.

2. The combination in a sterilizer, of a casing 100 connected to a source of liquid-supply, a conduit or conduits therein connected to an outlet, means for maintaining the level of liquid in the casing below an opening or openings into said conduit or conduits, means for applying heat to a portion of the liquid in the 105 casing and means for limiting the steam-freeing surface of said heated portion of liquid, substantially as described.

3. The combination in a sterilizer, of a liquid-containing casing, means for applying heat to a portion of the liquid in the casing, means for retaining the liquid normally at a predetermined level, means for carrying away liquid rising above said level, and means 115 whereby a portion of the liquid heated is confined within a space having but a relatively small steam-freeing surface, substantially as described. 110

4. The combination in a sterilizer, of a casing, means for applying heat to a definite volume of water therein, a partition within the casing confining the liquid heated to the highest temperature to a space having a relatively small steam-freeing surface, a conduit or series of conduits for removing liquid from the casing, a source of supply for delivering liquid to the casing, and means for guiding liq- 125 uid to the casing, and means for guiding liq-

uid raised above a predetermined level into said discharge-conduits, substantially as described.

5. The combination of a casing having within it a conduit open at one end and connected at the other end to an outlet, a conduit for supplying liquid to the casing, means for maintaining said liquid normally at a predetermined level in the casing, and means for 10 guiding said liquid into the conduit when it is caused to rise above its normal level, substantially as described.

6. The combination in a sterilizer, of a casing, means for heating liquid, a conduit or 15 conduits connected to an outlet and provided with a liquid-collecting vessel, means for normally maintaining the liquid within the casing at a predetermined level, and a device for 20 guiding liquid into said vessel whenever said liquid rises a predetermined distance above its normal level, substantially as described.

7. The combination in a sterilizer, of a casing, a conduit or conduits therein connected to an outlet, means for supplying liquid to the 25 casing, a float-chamber containing a float operative upon the supply-conduit, for normally maintaining the liquid within the casing at a predetermined level, with means for connecting the interior of the casing with the float- 30 chamber both above and below the normal fluid-level, substantially as described.

8. The combination of a casing having supply and discharge pipes, means within the casing for conducting fluid rising above a predetermined level to the discharge-pipe, means for heating the casing by fluid, means for maintaining the liquid in the casing normally below a predetermined level and means operated by the pressure within the casing for governing the supply of heating fluid thereto, substantially as described.

9. The combination of a casing, a casting having two chambers separate from the space within said casing, a source of supply for heated fluid connected to one of said chambers, a 45 series of tubes extending within the casing, and serving to connect said two chambers, with means for supplying fluid to and conducting it from said casing, substantially as described.

50 10. The combination of a casing, a casting having two chambers of which one is connected to a source of supply for heating fluid, a series of tubes extending from the first chamber, a second series in communication with 55 the first series and connected with the second chamber, an outlet-conduit from the second chamber, means for maintaining the fluid within the casing at a predetermined level, means for supplying fluid to be heated, and means 60 for conducting said liquid from the casing after it has been heated, substantially as described.

11. The combination in a sterilizer, of a casing, having conduits for fluid supplied to and 65 discharged from the same respectively, means

operative upon the fluid entering the casing for normally maintaining the top surface of said fluid below a predetermined level, a weir within the casing having a space on one side of it connected with the liquid-supply system 70 and having the space on its other side connected with the liquid-discharge system, and means operated by variations in the level of the liquid on the discharge side of the weir for regulating the flow of fluid therefrom, substantially as described.

12. The combination in a sterilizer, of a casing having a weir, a supply and a discharge conduit connected respectively to the spaces in communication with the two sides of said 80 weir a device governed by the changes in the level of the fluid on one side of the weir for controlling the supply of said liquid, and means operated by fluid on the other side of the weir controlling the discharge of said fluid 85 from the casing, substantially as described.

13. In a sterilizer, the combination of a casing, a weir within the same, means for heating the fluid on one side of said weir, means for automatically maintaining the level of the 90 fluid to be heated at a level normally below the edge of the weir, and means for automatically preventing the liquid on the other side of the weir from falling below a predetermined level, substantially as described. 95

14. The combination in a sterilizer, of a casing having a conduit within it formed to act as a weir, a pipe connected to the interior of the conduit and a second pipe connected to the space surrounding said conduit, with a float-chamber containing a float operated by changes of fluid-level in the space around the conduit, a second float-chamber having a float operated by changes of the level of the fluid within said conduit, and valves in said two pipes operated 100 respectively by said floats for controlling the two levels of said fluid within the casing, substantially as described.

15. The combination in a sterilizer, having within it a weir, of two float-chambers each 110 connected with the space above the weir and also with the liquid-filled spaces below said weir, a supply and a delivery pipe connected respectively to liquid-containing spaces on the two sides of the weir, and a valve in each of 115 said pipes having floats within said float-chambers for controlling the flow of liquid through the casing, substantially as described.

16. The combination in a sterilizer, of a casing having within it a partition, means for heating liquid within one of the spaces formed by said partition, a weir in the casing, a float-chamber, a float therein having means whereby liquid to be heated is normally maintained below the level of the weir, and a connection 120 between the float-chamber and the casing, said connection being made to that portion in the interior of the casing divided off from the source of heat by the partition, substantially 125 as described. 130

17. The combination in a sterilizer, of a casing including a casting having within it chambers of which one is connected to a source of supply for heating fluid, a series of tubes connecting said chamber with another chamber in the said casting, an outlet from said second chamber, and means for collecting liquid condensed in the first chamber and discharging it into the second chamber, substantially as described.
18. In a sterilizer, the combination of a main casing, a casting having chambers of which one is in connection with a source of supply for heating fluid, a series of openings in the second chamber of said casting having tubes closed at one end and extending into said main casing, a second series of tubes within the first series extending into openings in the first

chamber, an outlet-conduit from said second chamber, with means for retaining liquid within the casing above the level of said tubes, substantially as described.

19. The combination of a casing having within it a partition provided with openings, a series of tubes held at one end in said openings and free at their other ends, with a movable sheet having openings loosely receiving the free ends of said tubes, substantially as described.

In testimony whereof I have signed my name to this specification in the presence of two subscribing witnesses.
